Primary Examiner — Eric L Goodman*Assistant Examiner* — Sarah L Smith(74) *Attorney, Agent, or Firm* — Alston & Bird LLP(57) **CLAIM**

We claim the ornamental design for a dome light, as shown and described.

DESCRIPTION

FIG. 1 is a perspective view of a dome light showing our new design, shown in a wall-mount configuration;

FIG. 2 is a front elevation view thereof;

FIG. 3 is a right side elevation view thereof;

FIG. 4 is a left side elevation view thereof;

FIG. 5 is a top plan view thereof;

FIG. 6 is a bottom plan view thereof;

FIG. 7 is a perspective view of another embodiment thereof, shown in a ceiling-mount configuration;

FIG. 8 is a front elevation view thereof;

FIG. 9 is a rear elevation view thereof;

FIG. 10 is a right side elevation view thereof;

FIG. 11 is a left side elevation view thereof; and,

FIG. 12 is a bottom plan view thereof.

The broken lines illustrate features of a dome light that form no part of the claimed design.

1 Claim, 10 Drawing Sheets(56)
